UNITED STATES PATENT OFFICE.

EDWARD S. COBB, OF WHITTIER, CALIFORNIA.

RAILWAY INTERSECTION.

1,074,083.

Specification of Letters Patent. Patented Sept. 23, 1913.

Application filed March 5, 1913. Serial No. 751,988.

To all whom it may concern:

Be it known that I, EDWARD S. COBB, a citizen of the United States, residing at Whittier, in the county of Los Angeles, State 5 of California, have invented new and useful Improvements in Railway Intersections, of which the following is a specification.

This invention relates to an intersection construction for railways and the like; and 10 relates particularly to a method and construction of forming a continuous rail and causing continuous track action on any sort of intersection.

It is the prime object of my invention to 15 provide a construction which is simple, efficient and durable, and which will provide continuous rail action at any and all crossings and provide rail intersection joints of such nature so as to avoid all shock, wear 20 and deformation of the rails and the wheels passing over them.

The fundamental of this particular invention is the provision of movable rail portions directly adjacent the individual rail intersections, these movable rail portions directly abutting the ends of the rails at their junctions and being mounted so as to swing in the vertical planes of the respective rails about a pivotal point located under the rail 30 intersection. I provide such a movable rail portion for each rail at each intersection; and the general arrangement is such that either one or the other of the movable rail portions will be moved into direct engagement with the end of its corresponding rail at the junction, or may be moved about its pivotal support so as to move its engaging end from the intersection to leave a free space through which a flange of a wheel 35 traveling over the other rail may pass. In 40 an ordinary crossing construction including two intersecting pairs of two parallel rails each, each of the sections of rail between individual rail intersections will include two 45 of these oscillating rail portions; and in my preferred form of construction, that said section of each rail consists entirely of two oscillating rail portions. I provide suitable mechanism for operating these oscillating 50 rail portions in such manner that when one of the intersecting pairs of rails is connected through to effect continuous rail action, the other pair is disconnected by the movement of their oscillating rail portions away from

the rail intersections. In this operating 55 mechanism I also provide suitable means of locking the oscillating rail portions in their positions; and when the rail portions are in position to cause continuous rail action, they are supported and held with extreme solid- 60 ity, and the joint between the permanent rails and the movable portions are closed very tightly. In my invention I have also provided, in the construction of the individual rail intersections and the joining of 65 the movable rail portions therewith, for continuing unbroken the line of greatest wheel pressure in the tread face of the rails. All of the joints between the rail portions are made at an angle; so that there is no opportunity for a wheel to drop into any of the joints, should the joints not be pressed tightly together. Thus, with these two provisions, one for pressing the joint very 70 tightly and solidly together, and the other 75 for making the joint of a practical continuous nature, I completely avoid all possibilities of shock at the rail intersections.

The design and mechanism for pressing 80 tightly the joint together, is one of the distinguishing characteristics of this invention; it is a characteristic which enters largely into the essence of the form of which I am about to describe.

I have illustrated preferred forms of my 85 invention in the accompanying drawings; and I will describe preferred forms in the following detailed specification. And from this description the fundamentals of my invention may be easily contrasted with those 90 details which may be modified without altering the underlying nature of my construction.

In these drawings: Figure 1 is a sectional plan showing the application of my invention to a simple crossing. Fig. 2 is a vertical section taken on line 2-2 of Fig. 1. Fig. 3 is a somewhat similar view of a modified form of device. Figs. 4 and 5 are perspective details showing the construction 100 and operation of the individual rail intersections. Fig. 6 is a perspective showing a form of electrical control apparatus which may be used with my invention.

In the accompanying drawings I have 105 illustrated my construction as applied to a right angled crossing or intersection of two pairs of two parallel rails each; but it will

be seen that my invention may be applied to a crossing of any character and of any number of tracks or rails. In these drawings 10 and 11 may designate the rails of two intersecting pairs, each of the rails terminating at its junction with a rail of the other pair. I prefer, in this embodiment of my invention, to use the construction shown in Figs. 1 and 4. The rails 10 and 11 are joined, or 5 abut each other, on a plane 12 which may approximately bisect the angle between these two rails; and the rails then present, at their junction, a surface or surfaces 13 at approximately right angles to plane 12. 10 It is against this surface 13 that the movable, oscillating rail portions are adapted to be pressed; and it will be seen that the surface 13 cuts across the longitudinal tread axis of the rail at any angle. The rails 10 and 11 are preferably mounted upon the four corners of a box foundation 15 which carries suitable flanges to which the rails are secured, as at 16. In addition to being thus rigidly secured to the box 15, the rails 15 may be further secured together by a suitable heavy strap 17 bolted into the angle between each two meeting rails. The rails are thus rigidly secured together and secured to the foundation 15; and foundation 15 is so 20 constructed, being of a suitable heavy design and properly braced, that the different rails 10 and 11 are held solidly and rigidly in proper relation to each other.

My box foundation 15 is preferably constructed as is shown in Figs. 1 and 2, or as 35 is shown in Fig. 3, having a base 15^a and suitable side walls 15^b and brackets 15^c; and being provided with suitable cover plates 20 and 21. Cover plate 21 is preferably supported on columns or pedestals 22 extending upwardly from the base 15^a of the box foundation; and a suitable man hole and cover 23 is provided for immediate access to the interior of the box and to the mechanism contained therein.

For each of the rails 10 and 11 at each individual rail intersection, I provide a movable, oscillating, rail continuation portion 25, each of these portions being mounted to 50 oscillate about a center below the corresponding rail intersection, as will be herein-after described. I prefer to make the whole rail section between the individual rail intersections to consist each of two of these movable portions 25; the two movable portions 25 being joined together in such manner as effect substantially continuous rail action between them. I will describe the construction and action of one pair of these oscillating portions 25 and will then describe the co-operation of all the portions 25 and a preferred method of causing their action. 55 Each of the portions 25 has an upper tread part 26 which is adapted to form a continuation of the tread of the permanent rails 10

or 11. Below the tread part 26 there is a suitable web 27 constructed so as to afford great strength to the movable rail portions. Each of the rail portions has a bearing part 28 adapted to rest upon a cylindrical bearing surface 29. This bearing surface 29 is formed upon a suitable bracket 30 preferably forming an integral part of the box foundation 15 and constructed for great strength and solidity. The movable portions 25 each move on the bearing 29 about center 31; and links 32 are provided for holding the portions 25 down on the bearing surfaces 29. Each of the tread parts 26 has an end 26^a terminating in a plane at the same angle as that of the plane 13; so that the end of either one of the tread portions 26^a may be placed in engagement with the end surfaces 13 of the rails 10 or 11. It will be noted that the end 26^a of the movable rail portion 25 is of such configuration as to form practically a continuous rail when in engagement with the ends of rails 10 and 11; and that the line of greatest pressure on the tread (the center high line of the tread surface) is continued practically unbroken from the rails 10 or 11 onto the movable rail portions 25. The tread surfaces of the movable portions 25 are efficiently joined by providing a lapped joint between the two portions, as is best shown in Fig. 1. With this lap joint there is no break in the continuity of the tread axis; the parts 25^a of the movable rail portions 25 lying each on opposite sides of the central vertical plane of the rails.

It will be seen that the movable rail portions 25 may be placed either in the position shown in full lines or in the position shown in dotted lines in Fig. 2. In the position shown in full lines (the inoperative position) the ends 26^a are at a distance from the rail junctions so as to leave a space inside the rails for the passage of a wheel flange. The ends 26^a are seen to move in substantially a horizontal direction; while the inner overlapping portions 25^a are seen to move more or less vertically, the movement of the various portions being around the points 31 as centers. When the portions 25 are raised to the positions indicated in dotted lines in Fig. 2, then the ends 26^a may be forced into engagement with the ends of rails 10 and 11, and the tread portions 26 will form continuations of the tread portions of the rails 10 or 11, as the case may be. The movable portions 25 may be held against lateral motion, induced by the side thrust action of the end 26^a pressing against the diagonal plane 13, by tongues 27^b playing in apertures 27^c in the webs of rails 10 and 11. The construction and dimensions are such that, when the treads of portions 25 are in proper horizontal alignment, the joint between the portions 25 and the rails 10 and 11 will be very tight; 130

and this solidity of joining is of great importance as it entirely obviates the inception of a shock or jar which would, if started, soon break down the whole crossing construction.

The mechanism for moving the rail portions 25 preferably comprises an oscillating shaft 35 for each of the double sets of rail portions 25 corresponding with the pairs of rails 10 or 11. On each shaft 35 there are mounted two arms 36 each carrying a pin 37 forming a pivotal connective means with a strut 38. This strut 38 connects directly with a pin 39 to which the inner ends of compression links 40 are all attached. The outer ends of compression links 40 are pivotally secured at 41 to the webs 27 of movable rail portions 35. The whole arrangement is such that, with the parts in the position shown in Fig. 2, the links 40 are dropped down and pull the pivot points 41 in toward each other; but upon rotation of the shaft 35 in the direction opposite to that indicated by the arrow, the links 40 will be forced upwardly and will thereby force the pivotal points 41 apart and force the members 25 about the points 41 as centers until the members reach the positions shown in dotted lines. When these positions are reached, the arm 36 will have reached the position shown in dotted lines, as will have also the strut 38; and suitable stop shoulders 42 on the arm and strut will then engage to prevent further movement of the arm and strut; but the relative positions of arm and strut are such that downward pressure on the strut, or on the pin 39, will only tend to press the stop shoulders 42 more tightly into engagement and will not tend to rotate the shaft 35. In the position shown in dotted lines, the links 40 have passed to a position where the pin 39 is slightly above a line joining the pivot centers 41; so that inward pressure on the pivot centers 41 will not tend to create downward pressure on the pin 39. Thus the members 25 are doubly locked in position. When the members 25 are in the position shown in dotted lines the pin 39 bears against surfaces 43 and on the underside of web strengthening members 27 which are secured to the webs 27 where they overlap each other. These strengthening portions 27 bearing directly upon the pin 39, and the pin 39 being substantially supported by the strut 38 and the arm 36, the overlapping, or central parts of the rail portions 25 are very solidly supported in proper alignment.

In applying my invention to the ordinary form of railway intersections, there are four sets of movable rail portions 25, one set for each of the four intersecting rails; and the two opposite sets of portions 25 are to be operated simultaneously to effect continuity of the rails of either of the intersecting

tracks. Thus I arrange one of the shafts 35 to operate opposite sets of movable rail portions 25, while the other shaft 35 operates the other opposite sets of movable rail portions 25. I prefer to have such an arrangement as will coöperate all the movable rail portions; so that when one double set of said portions is thrown into position to cause continuity of rail action for one track, the other set is thrown out of that position.

I have indicated in the drawings directions of rotation of the two shafts 35 for lowering, or throwing out of operative position, the corresponding movable rail portions 25; rotation in the opposite direction raising the corresponding movable rail portion to operative position. I suitably interconnect the two shafts 35 so that when either is rotated in the direction indicated, the other is rotated in the opposite direction; and I may do this through the medium of suitable gearing connections as is indicated at 50 and 51. I may cause suitable operation of the whole system by means of a motor 52 connected by suitable gearing 53 with either of the shafts 35. The motor may be controlled from a distant point by any suitable means, either manually or by operation of a car rolling over the track. Either of these means is well known and requires no detailed explanation here. In order to limit the operation of the motor to rotate the shafts 35 only through the desired angles of rotation, I may make use of some suitable cut off device such as is illustrated in Fig. 6. I may employ a suitable commutator 60 having thereon two pairs of collector rings 61 and 62 and two pairs of segments 63 and 64. Suitable brushes 65 and 66 may engage the collector rings 61 and 62, and from these brushes wires 67 and 68 may lead to the motor 52, being connected thereto in such manner that supply of current through one set of wires will operate the motor in one direction and supply through the other set of wires will operate the motor in the other direction. The segments 63 and 64 may be engaged by suitable brushes 69 and 70 and wires 71 and 72 leading from these brushes will form the means of supplying current to the motor for operation of the track intersecting mechanism. In the form shown in the drawings, the shafts 35 require a rotation of approximately 90 degrees, or slightly less; and it will be seen that the segments 63 and 64 are so arranged that, on a travel of the commutator of slightly less than 90 degrees in either direction, one or other of the sets of brushes 69 or 70 will be out of engagement with the corresponding segments. Thus, the arrangement may be such that if current is supplied to the wires 72, it will pass through brushes 70, segments 63, commutator connections 75, collector rings 62, brushes 66 and wires 68 to the motor; which

will operate the motor in a direction to turn the shafts and the commutator in the direction indicated by the arrow. This will cause the rotation of the segment 63 under the brushes 70; and when the ends of the segments have passed from under the brushes, the circuit will be broken and the motor will cease operation of the mechanism. During this rotation, the segments 64 will have 10 passed under the brushes 69 and will be thus in electrical contact for the next operation of the motor. The next operation will be caused by sending current through the wires 71, which will supply current to the 15 motor through brushes 69, segments 64, commutator connections 76, collector rings 61, brushes 65, and wires 67; and the motor will then rotate in the direction opposite to that which it rotated before, and the mechanism 20 and the commutator will be moved back to its former position, the circuit being broken when the ends of the segments 64 pass from underneath brushes 69.

In Fig. 3 I have indicated a modified form 25 of my invention, showing in that figure only one set of the movable track portions 25^a. The operation of this modified form is substantially the same as hereinbefore described, excepting that the mechanism for moving 30 the portions 25^a is somewhat different. For each of the sets of movable track portions I employ two shafts 35^a upon which I mount inter-engaging sectors 80 having stop shoulders 81 which engage each other as shown in 35 the drawings. When the stop shoulders engage each other, pivot pins 82 are in the position shown in full lines in that figure, and compression links 83 are in their uppermost positions, or approximately so. Links 83 40 are joined by pivot pins 84 each to one of the movable rail portions 25^a; so that, when the parts are in the position shown in full lines, the movable rail portions are in positions to effect a continuous rail action. 45 When in this position, each of the portions 25^a has a surface 85 which will rest upon the pin 84 belonging to the other portion 25^a; and thus portion 25^a is supported by each of pivots 84 in addition to being supported on 50 cylindrical bearing surface 29^a. This construction consequently affords great solidity of support for the movable rail portions. Another difference which may be particularly spoken of is the manner of connecting 55 the links 32^a. These links are pivoted at 31^a, as before, but are rigidly attached to the member 25^a; so that the members are thereby constrained to rotate about the pivot 31^a.

Having described my invention, I claim: 60 1. A rail joint construction, comprising a plurality of rails terminating in junction, and a continuation portion for each rail abutting the end of the rail at the junction, said continuation portion being pivoted below the rail junction to swing longitudinally

toward or away from the adjacent rail end in the vertical plane determined by the longitudinal axis of the corresponding rail.

2. A rail joint construction, comprising a plurality of rails terminating in a junction, and a continuation portion for each rail abutting the end of the rail at the junction, 70 said continuation portion being pivoted vertically beneath the rail junction to swing longitudinally toward or away from the adjacent rail end in the vertical plane determined by the longitudinal axis of the corresponding rail, and means to move said portions and lock them in position against the rail ends at their junction.

3. A rail joint construction, comprising a plurality of rails terminating in a junction, and a continuation portion for each rail abutting the end of the rail at the junction, 75 said continuation portion being pivoted below the rail junction to swing longitudinally toward or away from the adjacent rail end in the vertical plane determined by the longitudinal axis of the corresponding rail, and means to co-operatively move said portions about their pivots to and from the respective rails.

4. A rail joint construction, comprising a plurality of rails terminating in a junction, and a continuation portion for each rail 95 abutting the end of the rail at the junction, said continuation portion being pivoted vertically beneath the rail junction to swing longitudinally toward or away from the adjacent rail end in the vertical plane determined by the longitudinal axis of the corresponding rail, and means to co-operatively move said portions about their pivots to and from said rails so that when one of said portions is in engagement with its corresponding rail end the other is moved away from the junction of the rails.

5. A rail joint construction, comprising an intersecting pair of parallel rails each rail terminating at a junction with a rail 100 of the other pair, continuation rail sections extending between the individual rail junctions and comprising movable portions adapted to abut each junction end of each rail, said portions being pivoted vertically 110 beneath the individual rail junctions to oscillate longitudinally toward or away from the adjacent rail end in the vertical planes determined by the longitudinal axis of the respective corresponding rails, and means to move said portions to and away from the rail junctions.

6. A rail joint construction, comprising an intersecting pair of parallel rails each rail terminating at a junction with a rail 125 of the other pair, continuation rail sections extending between the individual rail junctions and comprising movable portions adapted to abut each junction end of each rail, said portions being pivoted vertically

beneath the individual rail junctions to oscillate longitudinally toward or away from the adjacent rail end in the vertical planes determined by the longitudinal axis of the 5 respective corresponding rails, and means to cooperatively move said portions to and away from the rail junctions, so that when the portions corresponding to one pair of rails are in position against the junction 10 ends of those rails the other portions are moved away from the junctions.

7. A rail joint construction, comprising an intersecting pair of parallel rails each rail terminating at a junction with a rail of 15 the other pair, continuation rail sections extending between the individual rail junctions and consisting wholly of two movable portions adapted to abut each junction end of each rail, said portions being pivoted below 20 the individual rail junction to oscillate longitudinally toward or away from the adjacent rail end in the vertical planes of the respective corresponding rails, and means to cooperatively move said portions to and 25 away from the rail junctions, so that when the portions corresponding to one set of rails are in position against the junction ends of those rails the other portions are moved away from the junctions.

8. In combination with intersecting pairs 30 of parallel rails each rail terminating at its intersection with a rail of the other pair, rail continuation sections between the individual rail intersections, each of said sections comprising a pair of rail portions pivoted below the rail intersections and adapted 35 to abut the ends of the rails at said intersections, and means including a pair of compression links pivoted to said portions and 40 to each other to move said portions about their pivots.

9. In combination with intersecting pairs 45 of parallel rails each rail terminating at its intersection with a rail of the other pair, rail continuation sections between the individual rail intersections, each of said sections comprising a pair of rail portions pivoted below the rail intersections and adapted 50 to move longitudinally toward or away from the ends of the rails at said intersections,

and operating means including a pair of links pivoted to said rail portions and to each other and means to move the common pivot of said links transversely to the line joining their points of connection to said 55 movable rail portions.

10. A rail joint construction comprising a plurality of rails terminating in a junction and having their end surfaces on a substantially vertical plane diagonal to each of the 60 rails, a continuation portion for each rail having a corresponding diagonal end adapted to abut the end of the rail at the junction, means to move the continuation portion longitudinally to and from the rail, and means 65 to confine the continuation portion against lateral motion induced by engagement of said diagonal ends.

11. A rail joint construction, comprising a plurality of rails terminating in a junction 70 and having their end surfaces on a vertical plane diagonal to each of the rails, a continuation portion for each rail having a corresponding diagonal end adapted to abut the end of the rail at the junction, said continuation portion being pivoted below the rail junction to swing longitudinally toward or away from the adjacent rail end in the vertical plane of its corresponding rail, and means to confine the continuation portion 80 against lateral movement induced by engagement of said diagonal ends.

12. In a device of the character described, a pair of intersecting rails each terminating 85 on a plane diagonal to each of the rails, and a longitudinally movable continuation portion for each rail; said portion having a corresponding diagonal end adapted to abut the end of the corresponding rail, and means to confine the continuation portions against 90 movement transverse to the corresponding rails.

In witness that I claim the foregoing I have hereunto subscribed my name this 25th day of February 1913.
